UNITED STATES PATENT OFFICE.

MORTIMER BYE, OF INDIANAPOLIS, INDIANA, ASSIGNOR TO THE ELI LILLY AND COMPANY, OF INDIANAPOLIS, INDIANA, A CORPORATION OF INDIANA.

INHALER.

1,134,993.

Specification of Letters Patent. Patented Apr. 13, 1915.

Application filed November 11, 1914. Serial No. 871,573.

To all whom it may concern:

Be it known that I, MORTIMER BYE, a citizen of the United States, residing at Indianapolis, Marion county, and State of Indiana, have invented and discovered certain new and useful Improvements in Inhalers, of which the following is a specification.

My invention relates to inhalers and its object is to provide a container adapted to receive and hold menthol or a similar medicament both in a solid cake form and in powdered or broken condition for the purpose of enabling the menthol to be used as a pencil or for inhaling purposes and the invention also aims to provide means for obtaining a more effective inhalation than is usual with such devices. To these ends my invention is embodied in preferable form in the device hereinafter described and illustrated in the accompanying drawings.

In these drawings Figure 1 is a perspective view of a menthol holder; Fig. 2, a side view in elevation of the device with part of the cover or case removed; Fig. 3, an edge view of holder and case; Fig. 4, a top plan view of the holder shown in Fig. 1 and Fig. 5, a vertical section through the complete device.

Referring to the drawings, 1 is a hollow metal rectangular holder open at one end and closed at the other end by an end wall 2 which is rounded off laterally and at the ends. Openings 3 are formed in the end wall and these openings are spaced apart longitudinally of the end wall a sufficient distance to fit both nostrils and of a size and shape to simultaneously fit the nostrils when the holder is pressed against the lower part of the nose of the user. This arrangement permits an inhalation to be drawn in through both nostrils at the same time. The body of the holder, adjacent the closed end and inwardly approximately to the center of the holder is provided with a series of apertures 4, through which air is drawn into the holder. The holder is turned with the closed end down and small pieces of menthol 5, placed in the same, until the holder is about half filled. Then a solid cake of menthol 6 is forced into the holder at the other end, its inner face constituting a base for the broken pieces of menthol and

its outer end, projecting beyond the holder to form a pencil which may be directly applied.

The holder is adapted to be inclosed within a case which consists of a box having two removable slip members 7 and 8 adapted to fit over the holder and having their inner edges abutting when the box is closed.

The powdered or broken menthol at one end of the holder provides a mass into which the air is drawn more intimately and from which the material is more readily absorbed and carried along by the inhalation than in such arrangements as employ merely a solid cake. The openings in the end of the holder permit the device to be applied to both nostrils at the same time thus increasing the convenience of use.

In operation one or the other of the cover parts 7 and 8 is slipped off, according to whether the article is to be used as an inhaler or a pencil, and either the apertured end 3 applied to the nostrils and the air drawn through openings 4 and through the menthol in the holder, or the projecting end of the cake 6 used as a pencil.

Having thus described my invention, what I claim is,

A medicament container comprising a hollow rectangular holder open at one end and having a solid cake of medicinal material inserted into the holder at said open end, the inner end of said cake being projected into the interior of the holder and forming a base for a supply of lumps of medicinal material, said holder having a closing wall at the other end provided with a pair of nostril engaging openings spaced apart longitudinally of said end wall and said holder having apertures in its side walls between the end of the cake and the closing wall for the purpose of admitting air to the lumps of material.

In witness whereof, I have hereunto set my hand and seal at Indianapolis, Indiana, this 15th day of October, A. D. nineteen hundred and fourteen.

MORTIMER BYE. [L.S.]
